(57) **CLAIM**

The ornamental design for an adjustable light, as shown and described.

DESCRIPTION

FIG. 1 is an upper perspective view of a first embodiment of an adjustable light;
FIG. 2 is another upper perspective view of the adjustable light in FIG. 1 shown separately for ease of illustration;
FIG. 3 is a lower perspective view of the adjustable light shown in FIG. 2;
FIG. 4 is a front view of the adjustable light shown in FIG. 2;
FIG. 5 is a rear view of the adjustable light shown in FIG. 2;
FIG. 6 is a right-side view of the adjustable light shown in FIG. 2;
FIG. 7 is a left-side view of the adjustable light shown in FIG. 2;
FIG. 8 is a top view of the adjustable light shown in FIG. 2;
FIG. 9 is a bottom view of the adjustable light shown in FIG. 2;
FIG. 10 is an upper perspective view of the adjustable light shown in FIG. 2, illustrating the adjustable light in an alternate configuration;
FIG. 11 is an upper perspective view of a second embodiment of an adjustable light;
FIG. 12 is another upper perspective view of the adjustable light in FIG. 11 shown separately for ease of illustration;
FIG. 13 is a lower perspective view of the adjustable light shown in FIG. 12;
FIG. 14 is a front view of the adjustable light shown in FIG. 12;
FIG. 15 is a rear view of the adjustable light shown in FIG. 12;
FIG. 16 is right-side view of the adjustable light shown in FIG. 12;
FIG. 17 is a left-side view of the adjustable light shown in FIG. 12;
FIG. 18 is a top view of the adjustable light shown in FIG. 12; and,
FIG. 19 is a bottom view of the adjustable light shown in FIG. 12.
The broken lines shown in the figures illustrate portions of the adjustable light and form no part of the claimed design.
